CLAIM

The ornamental design for a cover for an air compressor, as shown and described.

DESCRIPTION

FIG. 1 is a perspective view of a cover for an air compressor showing our new design;

FIG. 2 is an end view; and,

FIG. 3 is a side view.

The broken line showing of an air compressor and associated equipment in FIGS. 1-3 is included for the purpose of illustrating environmental matter and forms no part of the claimed design.
